Application December 8, 1938, Serial No. 81,637

To all whom it may concern:

Be it known that I, Jules Glaenzer, a citizen of the United States of America, residing at New York city, in the county and State of New York, have invented a new, original, and ornamental Design for a Brooch or Similar Article of Jewelry, of which the following is a specification, reference being had to the accompanying drawing, forming part thereof.

Figure 1 is a front elevational view of a brooch or similar article of jewelry showing my new design.

Figure 2 is a plan view of Figure 1.

Figure 3 is a section on the line 3—3 of Figure 2.

Figure 4 is a section on the line 4—4 of Figure 2.

The characteristic feature of my design resides in a brooch of the configuration shown, to which the appearance of action or motion is imparted by the laterally offset sweep of the flame of the torch.

I claim:

The ornamental design for a brooch or similar article of jewelry, as shown and described.

JULES GLAENZER.
